JUMP AND TRAP WIRE

Frank W. E. Hoeselbarth, Carlisle, Pa., assignor to C. H. Masland & Sons, Carlisle, Pa., a corporation of Pennsylvania

Application September 13, 1955, Serial No. 534,093

4 Claims. (Cl. 139—44)

The present invention relates to transverse pile wires for weaving pile fabrics such as carpets, rugs and the like.

A purpose of the invention is to permit selective cutting or non-cutting of pile projections of different span length.

A further purpose is to permit cutting of normal pile projections by a knife at the end of the wire remote from the head, and passing float pile projections without cutting.

A further purpose is to provide a trap opening extending from a mouth in the upper portion of the wire in a rearwardly direction, locate a knife at the rearward end of the trap opening and suitably along the bottom, and provide a shield above the knife and extending over the rearward end of the mouth opening.

A further purpose is to locate the forward end of the shield above the top of the portion of the wire forward of the mouth of the trap opening.

A further purpose is to locate the forward end of the shield somewhat below the top of the portion of the wire forward of the mouth of the trap opening.

Further purposes appear in the specification and in the claims.

In the drawings I have chosen to illustrate a few only of the numerous embodiments in which my invention may appear, selecting the forms shown from the standpoints of convenience in illustration, satisfactory operation and clear demonstration of the principles involved.

Figure 1 is a fragmentary side elevation of a wire according to the invention.

Figure 2 is a fragmentary top plan view of the wire of Figure 1.

Figure 3 is a view of Figure 1 showing a modification.

Figure 4 is a warpwise conventional weave diagram showing a weave in which wires according to the invention are utilized.

Describing in illustration but not in limitation and referring to the drawings:

In the weaving of carpets and rugs and other pile fabrics, it is conventional practice to provide wires which are in some cases cutting wires, since they have cutters at the ends remote from the head and in other cases are non-cutting wires without such cutters. Other wire variations consist of the provision of raised portions or flags on non-cutting wires beyond the shed at the end remote from the head, and the provision of wavy or serrated portions on the tops of the wires in the shed.

It is not possible in ordinary weaving practice to selectively cut pile projections raised from a wire and where selective cutting is desired it has been the practice to introduce two wires, a cutting and a non-cutting wire, raising some of the ends over one of the wires and other ends over the other wire or over both wires. This procedure is tedious and expensive as it slows up the weaving operation.

The present invention is designed to permit making cut and uncut pile projections in the same transverse row by providing a wire which will cut short span pile projections such as normal pile projections, and, because of

2

their greater looseness, will leave longer span pile projections uncut. Thus high floats can be retained uncut, or, by suitable adjustment of the length of the trap and the position of the shield, long high floats can be left uncut and short high floats can be cut.

The wire of the invention can in all respects be a conventional transverse pile wire such as a straight wire, wavy wire, high wire, low wire, or the like, having a conventional head (not shown) to permit the pulling of the wire, with a special construction at the end remote from the head as shown.

Considering first the form of Figures 1 and 2, the wire body 20 is pulled in the direction of the arrow 21 which extends toward the head. Near the end remote from the head the top portion curves downwardly at 22 to form a trap opening 23 which has a mouth 24. The bottom of the trap opening flattens out and suitably curves upwardly at 25 and near the rear at 26 has a reverse curve. A portion of the wire above the trap opening now projects forwardly to form a shield 27 which terminates in a suitably blunted or curved forward shield projection 28 which forms the rear of the mouth opening. The shield in the form of Figures 1 and 2 has a horizontal top portion 30 and then bulges upwardly in a slight hump 31, and then the entire wire curves off at the rear end, first gradually at 32 and then abruptly at 33.

The bottom of the trap opening has a slot 34 which receives a knife 35, suitably a razor blade having an edge 36 which projects rearwardly and upwardly and terminates in a converging saddle 37 at the rear of the exposed portion of the knife where any pile projections entering the trap which remain uncut to that point are finally cut.

In the form of Figure 3, the forward projection 28' of the shield 27' is lower than the top edge 38 of the portion of the wire within the shed, so that a pile warp end which is not to be cut, such as a float end, can drop somewhat at the mouth opening 24' and still pass over the shield remaining uncut. In the form of Figures 1 and 2, however, the forward end 28 of the shield is slightly above the top edge 38 of the portion of the wire in the shed, so that if the pile projection drops perceptibly as it passes over the mouth opening it will be carried into the trap. The exact position at which the forward end 28 or 28' of the shield is located will determine the character of pile projection which will remain uncut. This position can if desired be made adjustable by bending the shield up or down, or in any other suitable manner.

It will be evident that the extent of the mouth opening 24 or 24' lengthwise of the wire will also control the tendency of the pile warp end to enter the trap or to pass over the trap and this can be suited to the particular weave. The mouth opening 24' is narrower than the mouth opening 24.

Figure 4 illustrates a suitable pile fabric in which wires 40 according to the invention raise a pile end 41 in normal pile passing up between two adjoining upper lefts 42, and a pile end 43 forms high floats 44 remaining up over, in this case, two adjoining upper wefts. Binder warp sets 45 and 46 hold together the upper wefts 42 and lower wefts 47. Stuffer warps are provided at 48.

It will of course be understood that the floats may be longer or shorter floats if desired and they may if desired be intermediate floats in the sense that the pile warp ends remain up over one wire and then float under the next wire or succeeding wires.

In operation, when for example, the wire 40' is withdrawn from the fabric, the relatively tight normal pile projections 41 will enter the trap and be cut by the

cutter as the wire is pulled while the floats 44 being relatively looser will escape the trap and not be cut.

In view of my invention and disclosure, variations and modifications to meet individual whim or particular need will doubtless become evident to others skilled in the art, to obtain all or part of the benefits of my invention without copying the structure shown, and I, therefore, claim all such insofar as they fall within the reasonable spirit and scope of my claims.

Having thus described my invention, what I claim 10 as new and desire to secure by Letters Patent is:

1. A transverse pile wire having a head at one end, and having at the end remote from the head a trap opening with a mouth at the top of the wire, a knife in the trap opening adapted to cut pile warp ends entering 15

the trap opening, said wire having a shield above the knife extending from the rearward end of the mouth of the trap opening toward the rear of the wire.

2. A wire according to claim 1, in which the knife extends rearwardly and upwardly.

3. A wire according to claim 1, in which the forward end of the shield rises above the top of the portion of the wire forward of the trap opening.

4. A wire according to claim 1, in which the forward end of the shield is below the level of the top of the portion of the wire forward of the trap opening.
